Specification of Letters Patent.

Patented Aug. 25, 1914.

Application filed August 10, 1908. Serial No. 447,749.

To all whom it may concern:

Be it known that I, GEORGE KERR ANDERSON, a citizen of the United States, residing in Memphis, Shelby county, Tennessee, have 5 invented certain new and useful Improvements in Shorthand Type-Writing Machines, of which the following is a specification.

The object of this invention is to effect 10 certain improvements in the construction and operation of shorthand typewriting machines, and the invention resides in the novel features of construction and operation set forth in the following specification and 15 claims, and illustrated in the annexed drawings, in which—

Figure 1 is a general plan view of my shorthand typewriter, minus the re-winding mechanism; Fig. 2 is a longitudinal section 20 on the line 2—2 of Fig. 1; Fig. 3 is a detail side view of the re-winding mechanism; Fig. 4 is a detail section view of same; Fig. 5 is a detail front view of same; Fig. 6 is a detail plan view of type bars and journal block; 25 Fig. 7 is a side view of same; Fig. 8 is a sectional view on the line 8—8 of Fig. 6; Fig. 9 is a detail portion of journal block; Fig. 10 is a plan view of feed frame; Fig. 11 is a sectional view on the line 11—11 of Fig. 30 10; Fig. 12 is a plan view of the type-carrying frames; Fig. 13 is a section of same on the line 13—13 of Fig. 12; Fig. 14 is an enlarged diagrammatical view of the keyboard, showing the various colors of letters 35 and numerals. Fig. 15 is a detail side view of a portion of the shift keys, as engaged in shifting one of the type carrying frames. Fig. 16 is a detail side view, enlarged, of the mechanism for shifting the left-hand 40 type-frame; Fig. 17 is an enlarged plan view of same; Figs. 18, 19 and 20 are views of the improved keyboard, showing new grouping of finger-keys and shift-keys, &c.

A indicates the base of the machine, which 45 is provided with the up-right side-plates. B, B, and to which base the guide-block C is secured. Through this guide-block a number of slots or grooves are cut, preferably twenty, one for each printing key and one 50 for each shift key, as shown in Figs. 1 and 6, and these slots are intersected at right angles by holes for the pivot-wires C² and C⁴ on which the printing keys and the shift keys are hung. The hole for the pivot wire 55 C³ extends through the guide-block from end to end, while the hole for the pivot-wire

C⁴ extends only part of the way, as shown in Figs. 6 and 9; also in Fig. 8. Holes of greater diameter than the slots are drilled in the pivot block in two rows, as shown in 60 Figs. 6 and 9, and spiral springs are inserted in these holes beneath the key-bars, as shown in Fig. 8, which raise the key-bearing end of each bar and cause the other end to rest, in the case of the printing keys, W, on the 65 pad X, and in the case of the shift keys, on the stop-pins A² and A³, provided for that purpose. A portion near the rear end of each printing key is flattened as shown in Fig. 6, so as to present a flat surface to the 70 face of the type, and beyond this, at the extreme end of the printing key, the upper part is cut away as shown in Fig. 7, making a recess about a quarter of an inch long and a sixteenth deep for the cross-rod N of the 75 feed frame F to rest in so that the strip of paper being fed through the machine will pass easily over it. The slots for the key-bars in guide-block C are cut parallel to each other and at substantially equal distances 80 apart, the distance between each slot being about the same as the thickness of a key-bar, and as the rows of type on the type-frames are about the same distance apart, this brings each key-bar under its proper 85 letter with very little adjustment, avoids crowding the ends of the bars, and in making the machines enables the manufacturer to cut all the slots in the guide-block at one 90 operation, by using a gang of saws. The 95 end of the key-bar to which the button is secured is bent upward as shown in Figs. 7 and 8, and in order to bring these key-buttons in position where all of them can be conveniently struck at one time, the key-bars are made of various lengths and are 100 bent outward in pairs near the point where they leave the guide-block C, as shown in Fig. 1.

The feed-frame, F, is pivotally mounted 100 beneath the keys on a rod A⁷ which passes through the sides B of the main-frame A, as shown in Figs. 2, 16 and 17, and around this pivot-rod, A⁷ is a coiled spring, A⁸, which causes the outer end of the feed frame 105 to bear down on the ends of the printing keys W, as shown in Figs. 2 and 16. The construction of the outer end of the feed-frame F is as follows: The cross-piece, M, bent down at each side, is riveted to the 110 ends of the feed-frame F as shown in Figs. 10, 11 and 16. A pivot-rod, O², passes

through holes in the ends of the feed frame F, as shown in Figs. 10 and 11, and also through a large opening in the left-hand side of the machine, B, as shown in Figs. 1, 5 and 17, where it operates the re-winding mechanism as hereinafter explained. On this pivot-rod is mounted a roller O³ which may be made of a piece of tubing covered with rubber at each end, leaving an open 10 space in the middle as shown in Fig. 10, opposite the bent-out portion, M², of the cross-piece M. There is also revolvably mounted on this pivot-rod O², the pressure frame N, the lower portion of which rests 15 on the key-bars, while the upper arms rest against the cross-piece M. The feed-frame F is pivotally mounted on the rod A⁷ which passes through the sides B of the main frame, and the coiled spring A⁸ causes the outer end of the feed-frame (or the pressure frame N thereof) to bear down upon the outer ends of the printing keys W, as shown 20 in Figs. 2, 16 and 17. Above the outer end of the feed-frame F is secured in the sides 25 of the machine, B, by a screw or otherwise, the cross-rod K, which is provided with a flat-downwardly-projecting spur K², as shown in Figs. 1 and 2, which spur K² projects down into and a little below the open 30 space M³ shown in Fig. 10, and in line with the arms N² of the pressure frame N. Bearing against this piece K² so that the two form a clutch, is the circular piece K⁴, mounted on a piece of tubing K⁵, which in 35 turn is revolvably mounted on a pivot-rod which passes through the sides B of the main frame. A coiled spring K⁶ extending from the side of the machine, B, to the circular piece K⁴, causes the latter to bear downwardly against the spur K², and the curve 40 of the piece K⁴ is such that when it is pressed down at the point of contact with K² it tightens and forms a clutch, while if it is turned in the opposite direction—or 45 lifted—its pressure against K² is lessened, whence it follows that a strip of paper may be drawn upwardly through this clutch and meet with very little resistance, while any attempt to pull the strip downward would 50 instantly increase the pressure of K⁴ against K², or in other words tighten the clutch and thereby prevent the downward movement of the strip of paper. The action then of the feed mechanism is this: The roll of paper, 55 a, is held in position by the paper support, which consists of the holder b revolvably mounted on the standard c held in place by the sliding catch d; the strip of paper, e, passes between the guide arms i² under the 60 roller g, on between the key-bars and the typeframes, under the roller O³ of the feed-frame F, then up between the arms N² of the pressure frame N and the cross-piece M; and when one or more of the key-buttons of 65 the printing keys W is depressed, it lifts

the pressure frame N which rests upon the key-bars and in doing so causes the arms of said frame N² to press tightly against the cross piece M, and as these parts rise, draw the strip of paper upwardly through the 70 clutch formed by the contact of K² and K⁴. When the printing key W is released, the coiled spring A⁸ causes the feed-frame F to fall down again; and the pressure against the frame N being released, the arms N² of 75 said frame no longer grip the paper and it is held tight only by the clutch formed by K² and K⁴. The downward or backward movement of the strip of paper being thus prevented by this grip as described, the pressure of the roller O³ of the feed-frame F causes a sufficient amount of paper to unwind from the roll, a, to allow the feed-frame 80 F to return to its normal position (with the lower side of the frame N resting on the key-bars) thus moving the strip of paper forward beneath the type and presenting a fresh surface for printing upon. This feed has two advantages over the feed described 85 in my Patent No. 581,570; first, instead of pushing the paper, it is pulled up by a positive grip which holds the paper tight in two places while it is pulling it and releases it altogether the instant the pressure on the printing key is removed; second, the two 90 grips, the one for pulling the paper up (formed by the arms N² of the rectangular frame N and the cross piece M), and the grip for preventing the downward or backward movement of the paper (formed by K² 95 and K⁴ as described) are substantially on the same level and are therefore not liable to crimp the paper if it is too soft and thus fail to work, but will pull it through with equal facility whether it is thick or thin, 100 whole, torn or patched. The feed-frame F is also provided with the cross-piece f (made of a small rod or wire) beneath which the ink ribbon, h, passes, and this cross-piece, f, besides forming a stiffening rib for the feed-frame and acting as a guide for the ink-ribbon, by its up-and-down motion keeps it from binding against the type-frames and thereby facilitates its movement through the machine, as shown in Fig. 2. The ink-ribbon is wound around the ribbon-reels, i, i, 110 which are somewhat similar in construction to those shown in my Patent 581,570, and is caused to travel from one ribbon-reel to the other by the elastic friction belt, i³, as 115 shown in Fig. 2. The roll of paper, a, fits tightly on the paper-holder, b, thereby causing the paper holder to revolve as the roll unwinds; so that by passing the elastic belt, i³, from the spindle of the paper holder to 120 the pulley, i', of one of the ribbon-reels i, the ribbon-reel will also revolve causing the ribbon to wind upon whichever reel the elastic belt is connected with. In going from 125 one reel to the other the ink-ribbon, as shown 130

in Fig. 2, passes beneath the type-frames and beneath the cross-rod, f , of the feed frame, F , and is kept straight by the long guides, i^2 , shown in Figs. 1 and 2, at each side of the ribbon and through which the shafts of the ribbon reels pass. The strip of paper, e , travels faster than the ink-ribbon, and to prevent the paper carrying the ribbon along with it and clogging the machine, when both are going in the same direction, a spiral spring, i^1 is put on the forward ribbon-reel, as shown in Fig. 1, between the side of the machine, B , and the guide-bar, i^2 , thereby pressing the latter against the ink-ribbon and producing sufficient friction to prevent the paper carrying it along too fast. These guide-bars are practically parallel and the shafts of the ribbon reels pass loosely through them.

20. J indicates the shaft on which the type-segments or type-frames, G , I and H are mounted. This shaft passes through the uprights B at each side of the machine, making a tight fit, and the type-frames are all 25. securely mounted on said shaft, and are normally held against the stop-rod J^2 (extending across the machine parallel to the journal J), by the spiral springs, J^3 , J^4 and J^5 —except in the modification shown in 30. Figs. 16 and 17 to which reference will be hereafter made.

When the three type-frames, G , I and H , are in their normal position against the stop-rod J^2 , the first row of characters on 35. each of the frames would be directly above the flat ends of the printing key bars, W , sixteen in number, one letter facing each bar, so that if the machine were supplied with paper and ink-ribbon and the sixteen 40. printing keys were struck simultaneously, the following letters would be printed across the strip of paper:

S T D W C H R E A W V R N D S T

45. It will be noticed that these letters appear as the first character in each line or column on the key-buttons, W^2 , of the printing keys, W . To print the letters appearing above them in the various columns, the shift-keys are used, and for convenience, the letters on the shift-key, or part or the whole of the shift-key itself, may correspond in color to the letters which it is used to print, as shown in Fig. 14. For example, the second line of 50. vowels, O, U and I, appears green, on the key-board, and the shift-key used in printing these letters, (marked Vow's) is likewise lettered green so that the similarity of colors will immediately indicate to the eye of the 55. operator which shift-key to use. The printing characters are arranged on the type-frames in lines substantially as described in my Patent No. 581,576, so that, by using the shift keys, each of the printing keys can 60. be brought to bear against any one of the

characters in the line directly above it. A reference to the key-board will show what characters appear on the type-segments in transverse rows above each of the printing keys.

The operation of the shift-keys is as follows, beginning, for convenience on the right hand side, with the vowel shift. The vowels, being between the two groups of consonants, are carried by the central type-frame, I , the arm of which, I^2 , extends beyond the adjoining type-frame, H , as shown in Fig. 12, is bent at right angles and provided with an eye, I^3 , through which the journal, J , passes, and is again bent at right angles so as to bring its end above the end of the shift-key E . The object of making the central type-frame in this manner is partly to give it a long bearing and partly to get it in position to be operated by the shift key at the side of the machine. The shift key, E , is pivotally mounted in the guide-block, C , on the pivot-rod C^1 . A small rod, passing through the end of the shift-key, as shown in Fig. 8, securely soldered, and having the two ends so bent as shown,—one above and one beneath the stop pin A^2 , will limit the movement of the shift key; or these and the spiral spring, C^2 , may be dispensed with and the shift key held in normal position by the arm, I^2 , of the type-frame I , and its upward movement limited by the stop pin A^2 . The depression of the key-button of the shift key, E , will raise the other end, which, bearing against the arm I^2 of the type-frame I , will cause the latter to revolve until the letters Q, U, I are brought opposite the flat surfaces of the printing keys, at which point the upward movement of the shift key is stopped by the stop pin A^2 or the stop pin A^3 , which latter is used while at the same time the movement of the type-frame, I , is checked by the end of its arm, I^2 , coming in contact with the upper fork, Q^1 , of the figure-shift frame Q .

The type-frame H is provided with the arm H^2 , which projects to the side above the end of the shift-key H , which is pivotally mounted in the guide-block, C , on the pivot-rod C^1 , has no spiral spring beneath it, being held in normal position by the arm H^2 of the type-frame H , and its upward movement limited by the stop pin A^3 in the case of shift key E . When the shift key reaches this point the further revolution of the type-frame will be checked by the upper fork, Q^1 , of the figure-shift frame Q , and in the case of type-frame F , and the following letters will then be in position to print their respective keys, the rods not being odd to

After these two shift keys have been mounted, the pivot-rod, C^1 , through which passes through the screw-hole, C^2 , is held in place by being bent down upon the end of the

screw in C⁶ which secures the block C to the main frame A.

The frame Q, is pivotally mounted on the rod q which passes through the side-plates B and is secured in them. On the right hand side the space between the frame Q and the side-plate B is occupied by a spiral spring which presses the end of the shift-frame Q down on the stop pin Q⁴, in which position the end of the shift-frame Q will be immediately beneath the arms of the type-frames H and I, while the upper fork, Q⁴, of said frame Q will be in position to check the movement of the type-frames H and I at a given point, as already explained. By depressing the finger-piece Q² of the frame Q until the movement of said frame is checked by the stop pin q², the type-frames H and I will be turned until the following figures are brought into position opposite the printing-keys:

1 2 3 4 5 6 7 8 9

As soon as the shift-key is released, the spiral springs, J⁴ and J⁶ cause the type-frames H and I to return to their normal position against the stop pin J². Laterally, the type-frames are held in position in this way; the spiral springs J⁴ and J⁶ are distended before being put on, which presses the type-frame G up against the type-frame I, and presses its arm, I², up against the collar, J⁶, which separates it from the side-plate B; while the spiral spring, J⁶, keeps the type-frame H pressed up against the type-frame I. The frame Q is provided with the roller g, beneath which the strip of paper passes, facilitating its passage.

The type-frame G is provided with twenty-eight characters arranged in four rows of seven each. For the first row of letters, as already stated, no shift is required. The type-frame G has two arms, the arm Y, at the top of the frame, provided with the off-set Y², as shown in Fig. 12, and the arm X² at the lower side of the type-frame, which serves as a stop-arm or stop pin. The shift-keys which operate this type-frame are also provided with the stop-arms U² and V², as shown in Fig. 7, the lower ends of which rest on the pin A² when the shift-keys are at rest. The shift keys U and V are mounted in the block C on the pivot-rod C², and held in position by spiral springs as shown in Figs. 6 and 7. When the shift keys are at rest, their stops, V² and U², are both in the path of the stop pin Y², while striking the finger-button of either shift key lifts the stop out of the path of the stop-pin Y²; while if both shift keys are struck together, both their stops are moved out of the way and the type-frame will travel until its upper arm, Y, comes in contact with the stop pin Y², shown in Fig. 1. These stops are so spaced that

the stop V² brings the type-frame G into position for printing the following characters

S P B F G L R

and the stop U² brings the following letters into position for printing

S M N V K L Y

while the stop pin Y² brings into position the last line of letters or characters, namely,

S Q Z X J.

It will thus be seen that by arranging the shift-keys and stops so that their stops are exchanged, so to speak, the shift-key for line three carrying the stop for line two, and vice-versa, and arranging the stops so that the operation of a shift-key removes its stop from action, two shift-keys can be made to do the work of three, an increase of fifty per cent. in efficiency. The shift key U has to move the type-frame G only the space of one line, while the shift key V has to move it the space of two lines, and other things being equal, its finger-button, Y², would have to travel twice as far as the button U²; so to 90 equalize matters an off-set, Y², is made in the arm Y of the type-frame G, bringing the point of contact between it and the shift key V much nearer the shaft J than is the point of contact between the shift-key U and 95 the arm Y, and thereby giving the finger-buttons of both shift-keys about the same distance to travel.

It will be noticed that with the shift keys arranged as hereinbefore set forth, each 100 type-frame is held absolutely rigid; two stops or a shift and stop come into play at the same time, thus absolutely preventing the type-frame from springing back or forward after it has reached the stop and thereby spoiling the letter or printing an entirely different letter from what it would have printed had it been held rigid at the stop, as herein provided for.

At the rear of the machine is the 110 rewinding attachment, which will now be described, and is illustrated in Figs. 2, 3, 4 and 5. aa is the supporting rod, which at its lower end passes through both side plates, B, of the machine, and is held up by the spur bb which rests on the base of the machine, A. The arm cc is pivotally mounted on the pivot-rod dd of the supporting-rod aa, as shown in Figs. 3 and 5, so that when a printing key is struck, thereby 115 raising the feed-frame, the lower end of the arm cc which rests on the cross-rod, O², of said feed-frame, will also be raised and the upper end of said arm cc be correspondingly lowered, pressing down the 120 frame which carries the pawl ee and causing said pawl to engage with the next lower tooth of the ratchet-wheel ff. The frame

55 *gg* which carries the pawl *ee* may be made of a short piece of tubing that will fit the supporting-rod *aa*; and a wire securely soldered to said tubing and bent as shown 5 by Figs. 3, 4 and 5. When the frame *gg* has been pressed down by the movement of the arm *cc* until the pawl *ee* engages another tooth as above stated, as soon as the return of the feed-frame *F* to its normal 10 position releases the pressure of the rod *O'* upon the lower end of the arm *cc*, the spiral spring *hh*, shown in Figs. 4 and 5, pressing the frame *gg* upwardly, will cause the pawl *ee* to turn the ratchet wheel *ff* the space of 15 one tooth, the backward movement of said ratchet wheel being prevented by the stop-pawl *ii*, which is spring-operated and pivotally mounted on the short rod *jj* as shown in Figs. 3 and 5. The ratchet wheel *ff* and the re-winding plate *kk* are both revolvably mounted on the supporting rod *aa*; the re-winding plate being first mounted on the lugs *ll*, and the ratchet-wheel on a piece of tubing which extends from the frame *gg* 20 to the lug *ll*, thereby giving the ratchet wheel a long bearing. The motion of the ratchet-wheel is communicated to the re-winding plate *kk* through the medium of the spiral spring *mm* which fits loosely over 25 the tubing on which the ratchet wheel is mounted and one end of which engages with a screw that passes through the ratchet-wheel as shown in Fig. 5. The object of the spring *mm* is to keep the re-winding plate *kk* wound up, so to speak, so that it 30 will be constantly pulling the strip of paper with a steady, even pressure; also that it may be readily turned back to refer to notes. The end of the spring *mm* is arranged so 35 that when tightened by the turning back of the re-winding plate beyond a given point, it will slip past the end of the screw which holds it and thus allow the re-winding plate to be turned back indefinitely. The re-winding attachment is also arranged so 40 that it will wind up the paper faster than the machine feeds it through, which keeps the paper wound tight and would not be practicable without the use of the intervening 45 spring *mm*, because as soon as it gets so tight that the spring *hh* cannot turn the ratchet-wheel any farther, the pawl *ee* ceases to work while the spring *mm* continues to turn the re-winding plate *kk*, 50 gradually loosening up until the spring *hh* is again able to turn the ratchet-wheel, and after a few turns the same process is repeated. An important advantage arises 55 from using a long re-winding plate and from having on one side of it entirely unobstructed, because it permits the notes to be readily referred to and quickly slipped off the plate, and the end of notes is then in such shape that it can be torn in two at any 60 point; a hole made with an awl at one end and a string put through, in which condition they are substantially the same as the pages of a note book without the necessity of re-winding them. Another advantage of an oblong receiving plate over a short plate 65 or a skeleton receiving reel is that when the operator, in taking dictation, turns back to read what has just been dictated, several sentences are presented to the eye at one time without turning the plate, and if 70 changes or pencil interlineations are to be made, the plate presents a hard surface to write on and room for making them, without removing the notes from the reel and afterward replacing them, as would otherwise be necessary, but for which there would be no time in modern business. One of the 75 main advantages and objects in using the long re-winding plate is to re-wind the notes, not in a small roll, but a large coil 80 with a big open space in the center, thus permitting the coil to be readily flattened out or any part of the strip composing it referred to without taking the whole thing 85 apart. 90

Figs. 16, 17 and 18 show modifications in the means for shifting the type-frames; Figs. 16 and 17 referring to the left-hand type-frame, *G*, and Fig. 18 to the type-frames *I* and *H*. In this modification, the spiral spring, *J'*, moves the type-frame *G* away from the stop-rod *J'*, instead of toward it as described elsewhere, the type-frame, *G*, being returned to its normal position by the arm *P*, which is pivotally mounted on the shaft *K* and connected with the feed-frame *F* by the rod *T*, so that when a printing key is struck and the feed-frame *F* is raised, the arm *P* will be also raised and the feed-frame *G* will revolve until 100 checked by contact with one of the stops. In this modification it would be necessary that the shift-keys *U* and *V*, at their ends should have the flat surface shown in Fig. 16, upon which would rest the stop-arm *R*, 105 pivotally mounted on the shaft *q*, a piece of tubing, *Z*, being used to give a long bearing, and the arm *R* being held down on the shift keys by the coiled spring *Z'*. As the arm *R* rests upon both shifts, it will be 110 raised by the operation of either; but it is of such length that when neither shift is struck, it will stop the type-frame *G* at the first line of type, viz., 115

120 S T D W C H R

but when either shift key *U* or *V* is struck, the stop *R* is lifted out of the path of the arm *Y*, which proceeds until arrested by contact with another stop as heretofore explained. 125

Thus far I have described a machine with the keys arranged substantially the same as

in my Patent 581,570, but in Figs. 19, 20 and 21, I show a new and improved arrangement of the keys and key-board by which all the printing keys are operated by the fingers 5 and all the shift-keys by the thumbs instead of by the little finger, as in Fig. 1 of this application or by the little finger and palm of the hand, as in my previous patent, the advantage being that the thumbs are quicker 10 than either and will be more certain to complete the turning of the type-frame before the printing key reaches it. The prime object of this improvement is to bring the shift keys together in one group and to get them 15 near the center-line of the key-board, because the thumbs and the fingers contiguous to the thumbs are quicker in movement than the other fingers of the hand, and their finger-buttons might exchange places with 20 those of the keys now operated by the index finger of each hand (by a slight change in the construction of the machine) without departing from the spirit of this invention, though I prefer to put them under the 25 thumbs because it more clearly separates them from the printing keys. On the left-hand side the shift keys U and V are first bent outwardly after leaving the guide-block, as shown in Fig. 19, then curved 30 downwardly as shown in Fig. 20 so as to clear the printing keys, then they cross beneath the printing keys to the proper position to be operated by the thumbs as shown in Fig. 19. On the right hand side the same 35 course is followed with respect to the shift keys E and E², except that in order to bring the vowel shift key close to the vowel printing keys and the consonant shift keys close to the consonant printing keys, the vowel 40 shift, E, crosses beneath the consonant shift key, E², as shown in Figs. 19 and 21. Fig. 20 shows the shift-key V depressed, its stop, V² clear of the stop-arm Y² of the type-frame G and said arm in contact with the 45 stop U² of the shift-key U. The type-frame I is also shown in its normal position against the rear stop J². A partial view of the feed mechanism is shown in this figure. In this key-board I have put no springs 50 under the right hand shift-keys E and E²; their ends simply rest against the arms of the type-frames H and I, their upward movement being limited by the stop-pin A⁶. This arrangement of the key-board may be 55 used with shift-keys operating directly against the arms of the type-frames as shown in Figs. 19, 20 and 21, or with the modifications shown in Figs. 16, 17 and 18. On the re-winding device I use a plate in 60 preference to pins because it affords a solid, flat surface on which to interline notes, make pencil memoranda, &c. The spiral spring shown in Fig. 1, *nn*, prevents the re-winder from swinging back with the key-buttons

when the machine is held in a vertical position. This I claim as part of my invention. 65

As shown in Fig. 7, (and other figures) all the printing keys have, at the end beneath the type, on their upper side, a cut or depression, W², and in this recess the lower 70 side, N, of the feed-frame, F, rests, so that the strip of paper will have an unobstructed passage above it.

The upper portion of the paper holder being similar to that described in my Patent 75 581,570, is not shown here in detail.

What I claim as new and desire to secure by Letters Patent, is—

1. In a shorthand typewriter, the figure-shift frame Q, provided with guide-arms for 80 the strip of paper and the small roller g to facilitate its travel.

2. In a shorthand typewriter using a continuous strip of paper, a series of key-bars, a feed frame operated thereby for feeding the paper through the machine, and means for re-winding the paper, operated by the feed-frame.

3. In a shorthand type-writer a series of key-bars adapted to operate simultaneously 90 and a feed frame bearing on the key-bars and provided with a grip for gripping the paper when one or more of said keys are operated.

4. In a shorthand typewriter, a series of 95 key bars suitably mounted, having their outer ends resting side by side and provided on the upper side with recesses of uniform depth, in combination with a feed frame having a pressure frame pivotally mounted 100 therein opposite said recesses and adapted to rest in the recesses.

5. In a shorthand typewriter using a continuous strip of paper, a series of key-bars and a feed frame provided with an oscillating grip for moving the paper when the feed-frame is operated. 105

6. In a shorthand typewriter, a series of printing keys capable of simultaneous operation, a feeding device provided with a 110 grip for carrying the paper forward, and an independent grip for preventing the backward movement of the paper.

7. In a shorthand typewriter, a series of printing keys having their key buttons arranged conveniently for simultaneous operation, a feed-frame provided with a grip for moving the paper forward, and means for preventing the backward movement of the paper. 115

8. In a shorthand typewriter a type frame revolvably mounted on a shaft and provided with a plurality of arms projecting from said type frame at the end, in combination with a shift key adapted to bear against one 125 of said arms and revolve the type frame until the other arm comes in contact with a stop located in the line of travel of said sec- 120

- end arm for the purpose of limiting its movement, substantially as described: 65
9. In a shorthand typewriter, having a series of key-bars suitably mounted, the feed frame P and the pressure frame N pivotally mounted in said feed-frame, one side of which rests on the key-bars and the other against a portion of the feed-frame, forming a clutch substantially as shown and described. 70
10. In a shorthand typewriter using a continuous strip of paper, a series of printing keys, a device for feeding the paper through the machine operated by the printing keys, and a receiving plate for re-winding the paper after it has been fed through the machine. 75
11. In a shorthand typewriter a type-frame revolvably mounted on a shaft and provided with a plurality of pins or arms, in combination with a plurality of shift keys adapted to move said type frame by bearing against one of said arms and arrest its motion by contact with another of said arms. 80
12. In a shorthand typewriter, means for moving the paper forward and means for preventing the backward movement of same, consisting of the stationary cross piece K, K^a and the curving, spring-operated pressure bar K^b, K^c. 85
13. In a typewriting machine, a type-frame revolvably mounted on a shaft, a plurality of shift keys bearing against said type-frame or an arm thereof, and stops operated by the shift-keys for limiting the movement of the type-frame. 90
14. In a shorthand typewriter using a continuous strip of paper, means for feeding the same through the machine, means for re-winding the same, and the arm so pivotally mounted, and having one end in mechanical connection with the feed mechanism and the other in mechanical connection with the re-winding mechanism. 100
15. In a shorthand typewriter using a continuous strip of paper, means for feeding the same through the machine, means for re-winding the paper, said re-winding mechanism being supported by a frame which is revolvably mounted on the base of the machine, and an arm or lever mechanically connecting the feed mechanism to the re-winding mechanism. 105
16. In a shorthand typewriter using a continuous strip of paper, a series of key-bars, a feed mechanism operated thereby for feeding the paper through the machine and a long receiving plate for re-winding the paper, and means mechanically connecting the feed mechanism to the re-winding mechanism. 110
17. In a typewriting machine provided with a plurality of type-frames, a type-frame having a bearing on each side of an adjoining type-frame, one end of said type-frame being provided with printing characters and the other end being in mechanical connection with a shift key, as shown and described. 115
18. In a writing machine, a plurality of type-frames revolvably mounted on a shaft, a plurality of shift keys operating side by side for moving said type-frames, and an arm extending from the inner type-frame to one of the shift keys, said arm also having a bearing on the shaft. 120
19. In a writing machine provided with a plurality of type-frames revolvably mounted on a shaft and a plurality of shift-keys for moving same, an arm extending laterally from an inner type-frame across the adjoining type-frame, to one of the shift keys. 125
20. In a shorthand typewriter using a continuous strip of paper, means for feeding the paper through the machine and means for re-winding the same, the said re-winder being operated by a feed-arm in mechanical connection with the key-bars. 130
21. In a typewriting machine a type-frame revolvably mounted on a shaft, a plurality of shift keys bearing against said type-frame at different distances from the shaft, and a stop for limiting the movement of the type-frame. 135
22. In a short hand typewriter, a type-frame revolvably mounted on a shaft, a spring normally pressing said type frame against a rear stop pin, a shift key adapted to move the type frame in an opposite direction against the force of the spring, and another shift key provided with a stop for limiting the movement of the type frame. 140
23. In a shorthand typewriter the type frame revolvably mounted on a shaft, a spiral spring normally pressing said type frame against a rear stop and also against the adjoining type-frame, and a plurality of shift keys adapted to turn the type-frame against the force of said spiral spring and provided with stops normally in the path of the type-frame. 145
24. In a writing machine using a continuous strip of paper, a feed-frame provided with a grip for feeding the paper through the machine, and means for re-winding the paper. 150
25. In a shorthand typewriter, a movable type-frame, a plurality of stops limiting the movement of said frame, and means for removing either or both of said stops from the path of the type-frame, simultaneously with the operation of a printing key. 155
26. In a shorthand typewriter using a continuous ribbon of paper, means for supporting the roll, means for feeding the strip through the machine and means for re-winding the same, consisting of a spring operated 160

receiving reel, and means for tightening the spring which causes said reel to revolve.

27. In a shorthand typewriter, the type-frame G revolvably mounted on the shaft J, the rear stop pin J², the spiral spring J³ pressing the type-frame away from the stop J², and the arm P mechanically connected with the type-frame F, exerting a pressure in the opposite direction to the spiral spring J³.

28. In a shorthand typewriter using a continuous strip of paper, a series of key-bars, means for feeding the paper through the machine and separate means for re-winding the paper, both operated by the key bars.

29. In a writing machine using a continuous strip of paper, a series of key-bars, a feed mechanism for feeding the paper through the machine operated by the key-bars and means for re-winding the same operated by the feed mechanism.

30. In a shorthand typewriter using a continuous strip of paper and an ink ribbon, means for feeding the paper through the machine and separate means for re-winding the same, a support for the paper roll revolvably mounted on a shaft, reels for the ink ribbon mechanically connected with the paper roll support and moved thereby and guides for the paper and ribbon, substantially as shown and described.

31. In a writing machine using a continuous strip of paper and an ink ribbon, the two being of similar width and traveling in a similar course, two parallel guide arms supported by the ribbon reels and extending far enough beyond same to keep the ribbon and paper together.

32. In a shorthand typewriter using a continuous strip of paper, the holder b revolvably mounted on the supporting frame e, the guides i¹ supported by the ribbon reels and means for feeding the strip of paper through the machine.

33. In a shorthand typewriter, means for supporting a roll of paper, means for feeding the same through the machine a re-winding mechanism consisting of a receiving reel, a ratchet wheel, a spring for communicating the motion of the ratchet wheel to the receiving reel, and means for communicating the movements of the feed mechanism of the machine to the re-winding mechanism.

34. In a shorthand typewriter a series of key bars suitably mounted and having their outer ends resting side by side in combination with a feed frame pivotally mounted at one end and provided with a pressure frame pivotally mounted therein, which pressure frame rests on the key bars.

35. In a shorthand typewriter, a series of key bars and a feed frame the lower side of which rests on the key bars in recesses

provided for the purpose, said feed frame being provided with an opening above the portion resting on the key bars for the passage of a continuous strip of paper through said feed frame, substantially as shown and described.

36. In a shorthand typewriter, a series of key-bars the ends of which rest side by side, a type frame revolvably mounted above the central portion of the ends of said key-bars on a horizontal shaft, an additional type-frame mounted on the same shaft at each side of the central frame, and means for turning the central type-frame without moving the shaft or the adjoining type-frames.

37. The combination, in a paper feeding mechanism, of a series of key-bars, a grip for moving the paper in a given direction, means for transmitting motion from the key-bars to said grip, and means for preventing a retrograde movement of the paper.

38. In a writing machine using a continuous strip of paper, a series of key-bars, a feeding device independent thereof but operated thereby and provided with means for holding the paper and moving it in a given direction, in combination with means for preventing a retrograde movement of the paper.

39. In a writing machine using a continuous strip of paper, a feed mechanism comprising two grips mounted independently of each other and means for moving one grip up to the other.

40. In a writing machine using a continuous strip of paper, a feed mechanism comprising a gripping device for carrying the strip forward by gripping the same at a definite distance from the edge thereof, and a device for preventing the retrograde movement of the paper by gripping another portion of the strip, in combination with means for bringing the said grips together in an interlocking relationship.

41. In a writing machine using a continuous strip of paper, a feed grip provided with a pivotally mounted member, one portion of which rests upon or against the key-bars while another portion is caused to press against the paper when a key is operated.

42. In a writing machine provided with a plurality of type-frames revolvably mounted side by side, a type-frame provided with a plurality of arms projecting from the side thereof, a shift key for moving the type-frame by pressing against one of said arms, and a stop for checking the movement of the type-frame by coming in contact with another of said arms.

43. In a writing machine using a continuous strip of paper, a re-winding reel composed of a plurality of parts and means for transmitting motion from one of said parts

to another, in combination with means for feeding the paper through the machine and means for transmitting motion from the feeding mechanism to the re-winder.

44. In a writing machine using a continuous strip of paper, a series of key-bars, a feed mechanism operated thereby, means for rewinding the paper as it leaves the machine, and a rod or spur extending laterally from the feed mechanism to the re-winding mechanism for the purpose of operating the same.
45. In a writing machine using an ink

ribbon and a continuous strip of paper, means for feeding the paper and the ribbon 15 through the machine and parallel guide-arms supported by the ribbon reels for guiding the ribbon and keeping it in proper relation to the paper.

In testimony whereof I have signed my 20 name to this specification in the presence of two subscribing witnesses.

GEORGE KERR ANDERSON.
